DESIGN FOR A STOOL

Charles Eames, West Los Angeles, Calif., assignor to Evans Products Company, Detroit, Mich., a corporation of Delaware

Application May 20, 1946, Serial No. 129,871

Term of patent 14 years

(Cl. D15—8)

To all whom it may concern:

Be it known that I, Charles Eames, a citizen of the United States, residing in West Los Angeles, in the county of Los Angeles and State of California, have invented a new, original, and ornamental Design for Stool, of which the following is a specification, reference being had to the accompanying drawing, forming a part thereof.

Fig. 1 is a front elevational view of a stool, showing my new design.

Fig. 2 is a top plan view;

Fig. 3 is a bottom plan view; and

Fig. 4 is a side elevational view thereof.

I claim:

The ornamental design for a stool, as shown.

CHARLES EAMES.
